UNITED STATES PATENT OFFICE

156,753

AMPHIBIAN AIRPLANE

Robert Wendell Miller, Farmingdale, N. Y., assignor to Republic Aviation Corporation, Farmingdale, N. Y., a corporation of Delaware

Application December 30, 1944, Serial No. 117,199

Term of patent 14 years

(Cl. D71—1)

To all whom it may concern:

Be it known that Robert Wendell Miller, a citizen of the United States and a resident of Farmingdale in the county of Nassau and the State of New York, has invented a new, original, and ornamental Design for Amphibian Airplane, described and claimed in the following specification, and shown in the accompanying drawings wherein:

Fig. 1 is a plan view of an amphibian airplane embodying the present design, with the landing gear protracted;

Fig. 2 is a front elevation thereof with the landing gear retracted;

Fig. 3 is a side elevation thereof with the landing gear retracted;

Fig. 4 is a perspective view from the front with the landing gear protracted; and

Fig. 5 is a similar view from the rear.

What is claimed is:

The ornamental design for an amphibian airplane, substantially as shown.

ROBERT WENDELL MILLER.
